Primary Examiner — Michelle E. Wilson*Assistant Examiner* — Messina L Smith(74) Attorney, Agent, or Firm — Lawrence Cruz, Esq.; Ryan, Mason & Lewis, LLP(57) CLAIM

The ornamental design for a hair clip, as shown and described.

DESCRIPTION

FIG. 1 is a perspective view of a hair clip showing the new design in a closed configuration;

FIG. 2 is a perspective view of the hair clip in an open condition configuration;

FIG. 3 is a left side elevation view of the hair clip;

FIG. 4 is a right side elevation view of the hair clip;

FIG. 5 is a rear view of the hair clip;

FIG. 6 is a front view of the hair clip;

FIG. 7 is a top plan view of the hair clip; and,

FIG. 8 is a bottom plan view of the hair clip.

The broken lines in the drawing depict portions of the hair clip that form no part of the claimed design.
